ABSTRACT OF THE DISCLOSURE

The present invention relates to compositions of tris (hydroxymethyl) aminomethane with monocarboxylic aminated organic acids such as theophylline-acetic acid, thioctic acid, orotic acid and pangamic acid, the method of manufacturing the same, and the method of treating acidosis by administration of the same.

The present invention concerns new compounds of antiacidotic action such as the derivatives of tris (hydroxymethyl) aminomethane, of important therapeutic applications.

Constant blood pH is essential for the development of vital processes of the human organism. However, the acidosis produced either by abnormal accumulation in blood of ketone groups originating from the abnormal catabolism of fatty acids together with a deficiency in the metabolism of carbohydrates, either by failure in the mechanism regulating the blood and extra-blood pH.

In the first type of acidosis, the treatment can be directed to increase the pH and the alkali reserve, to promote the whole metabolism of the ketone bodies, or both, simultaneously.

In the second case, the treatment must be directed to increase the alkali reserve and to activate the extra-blood regulator mechanisms.

In general, the treatments used up to now were directed to normalize the pH by increasing the alkali reserve.

For instance, use was made of sodium bicarbonate which acts exclusively as a blood buffer, but it shows the disadvantage of being contraindicated in the acidosis of respiratory or renal nature and being devoid of intracellular buffer action.

In 1959, Nahas introduced the organic amines, among which—by its efficacy and non-toxicity—the tris (hydroxymethyl) aminomethane or THAM, which not only acts as a plasmatic buffer but also as an intracellular buffer.

However, the THAM shows some disadvantages in relation to its administration since its solutions are too alkaline and may provoke digestive troubles. On the other hand, it is not active against the causes of the acidosis.

To correct such disadvantages in the treatment of acidosis we have directed our investigation towards the synthesis of THAM derivatives having more effective therapeutic properties and being better tolerated.

In this way we have synthesized a series of THAM derivatives with organic acids acting on acidosis. The mentioned compounds not only reestablish the pH but

2

they are also active against the causes producing the changes, and they differentiate from the antiacidotic substances known so far.

The method of obtaining these compounds is essentially based on the direct reaction of the respective acid with tris (hydroxymethyl) aminomethane, either in the fusion state or in a suitable solvent.

These compounds can also be obtained by reacting the salts of the components by means of double replacement in a solvent that is suitable in each particular case.

The invention is illustrated, by the following examples:

EXAMPLE 1

200 g. of theophylline and 500 cc. of water are heated to ebullition and added to 100 g. of chloroacetic acid and small portions of sodium hydroxide 30% without discontinuing agitation and heating strongly for 10 minutes. Then keep slow ebullition for another 30 minutes.

The solution is then cooled in a drier, then filtered, the resulting crystals are washed with slightly acidified water and, finally, desiccated. The crystals thus obtained correspond to theophylline acetic acid.

100 g. of theophylline acetic acid perfectly dried are pulverized with 50.9 g. of tris (hydroxymethyl) aminomethane in a mortar until a homogenous mixture is obtained. The mixture is immediately transferred to a steel container in oil bath and heated to 150–175° C.

The mixture is constantly and vigorously agitated until a limpid liquid is obtained which is dropped, still scalding, into steel trays and, finally, is subjected to vacuum desiccation to preserve from moisture.

The desiccated product must be manipulated rapidly and in a very dry medium as it is very hygroscopic. In this way are obtained some 145 g. of tris (hydroxymethyl) aminomethane theophylline acetate.

EXAMPLE 2

26.0 g. of sodium theophylline acetate are dissolved in the smallest possible quantity of water, to which 15.8 g. of tris (hydroxymethyl) aminomethane hydrochloride is added.

Ebullition is maintained for 30 minutes; then 200 cc. of warm alcohol 96° are added, and the hot solution is filtered to separate the NaCl thus formed. The resulting solution is vacuum evaporated until a pasty mass of crystals is detached and then treated with absolute alcohol; the evaporation to dryness is repeated to eliminate the remaining water.

The efficiency is 88%.

The product thus obtained has been identified as the tris (hydroxymethyl) aminomethane theophylline-acetate of molecular weight 359.3, empirical formula

and structural formula:

White powder, hygroscopic, melting at 115° C., very soluble in water and warm alcohol, sparingly soluble in

Clinically, excellent results have been obtained with the tris (hydroxymethyl) aminomethane thiocotate, orotate and pangamate by its buffer and eumetabolic action in acidosis of metabolic or toxic type related with troubles of the liver function or of the metabolism of glucides. Likewise, in acidoketosis by fever, vomiting, ketonuria, dehydratations, denutrition, alcoholism, diabetic acidosis, post-anesthetic acidosis, etc.

We claim:

1. A composition of matter tris (hydroxymethyl) aminomethane theophylline acetate. 10
